UNITED STATES PATENT OFFICE.

SAMUEL D. HOUSE, OF MOUNT PLEASANT, TENNESSEE; MEDORA HOUSE ADMINISTRATRIX OF SAID SAMUEL D. HOUSE, DECEASED.

PERMUTATION LOCK.

Application filed January 5, 1923. Serial No. 610,836.

This invention relates to a permutation lock which is mainly designed for motor vehicles, though it may be used for other purposes, the general object of the invention being to provide means for preventing an unauthorized person from completing the ignition circuit to a motor or other electrical device and also for shutting off the fuel line to the motor.

10 A further object of the invention is to provide a combination lock for the device with means for changing the combination whenever desired.

This invention also consists in certain 15 other features of construction and in the combination and arrangement of the several parts, to be hereinafter fully described, illustrated in the accompanying drawings and 20 specifically pointed out in the appended claims.

In describing my invention in detail, reference will be had to the accompanying drawings wherein like characters denote like or corresponding parts throughout the several views, and in which:—

Figure 1 is a side elevation of the invention with parts in section.

Figure 2 is a section on line 2—2 of Figure 7.

30 Figure 3 is an enlarged sectional view with the bolt in its locked position.

Figure 4 is a longitudinal section showing the bolt in unlocked position.

Figure 5 is a section view of the casing 35 with the locking mechanism in elevation.

Figure 6 is a detail section through the casing of the relative positions of the electrical contacts.

Figure 7 is a transverse section on line 40 7—7 of Figure 1.

Figure 8 is a transverse section on the line 8—8 of Figure 1.

Figure 9 is a side elevation of the exterior of the case.

45 Figure 10 is a side elevation, partly in section of the band carrying the numerals for the combination disk.

Figure 11 is a side elevation of one of the combination disks.

50 Figure 12 is a longitudinal section through the disks showing the manner in which they are fitted together.

Figure 13 is an end elevation of the members shown in Figure 12.

Figure 14 is a perspective view of the 55 locking bolt and sleeve therefor, and

Figure 15 is a diagrammatic view of the wiring system.

In these views 1 indicates a casing which is suitably secured to the dash 2 of a motor vehicle. The front of the casing is formed by a door 3 which is hinged at one end and is provided with a lock 4 at its other end. This door is provided with a slot 5 and a window 6. A supporting frame 7 is arranged in the casing and a bolt 8 is slidably supported by said frame. This bolt carries a pin 9 which projects through a slot 10 in the frame and a spring 11 has one end fastened to the pin and its other end to a part of the frame and 65 tends to hold the bolt in its forward or unlocking position. The combination discs 12 are associated with said bolt and these discs are arranged on a sleeve 13 which is supported in the frame and is held against 70 movement therein. The discs are provided with key-ways 14 and the sleeve is provided with a key-way 15 to permit the passage of the spring latch 16 on the bolt. When the key-ways in the discs are out of alignment 75 with that in the sleeve the bolt is prevented from being moved and is held in locking position until the discs are moved to place their key-ways in alignment with each other and with that in the sleeve. Then the bolt can 80

be moved to unlocking position. The bolt is provided with a recess 17 to receive the head of the spring latch and said head is beveled so that the bolt can be moved to a locking position even though the combination discs are 85 in locking position as the beveled part of the head engaging the hubs of the discs will be forced into the recess 17 and thus permit the bolt to be moved to locking position. The first disc is provided with a long hub 18 which 90 is engaged by the hub 19 of the second disc and the third disc engages the hub 19 of the second disc. The ends of the hubs 18 and 19 do not extend entirely through the third disc and said third disc is provided with a 95 recess 20 for receiving the end of the bolt and the head of the latch when the bolt is in locking position. The discs fit snugly between the uprights of the supporting frame and thus the spring latch and the 100 key-ways are hidden from view at all times so that if a person should gain access to the interior of the box he would still be prevent-

105

ed from moving the discs to unlocking position by manipulating the spring latch or placing the parts in their proper positions by aligning the key-ways by sight. The first disc is provided with a recess 21 having beveled walls for causing the depression of the spring latch at the beginning of the locking movement. The combination figures are carried by the bands 22 which are placed 10 on the discs and are held thereon by the screws 23 and by the tongues 24 fitting in the grooves 25 in the discs. Thus by removing the discs from the sleeve and changing the position of the bands any desired combination can be set up for placing the discs in unlocking position. The discs will project through the window 6 in the door so that they can be easily rotated. The bolt is held in locking position by a latch 26 20 engaging a notch 27 in the bolt, said latch being carried by a bar 28 which has one end projecting through the door where it receives a knob 29 so that the bar can be manually rocked to release the latch 26. A handle 30 on the bolt projects through the slot 5 and this handle has a knob 31 thereon. Thus the bolt can be actuated by hand without opening the door. This handle passes through a slot 32 in one arm of a bell 30 crank lever 33 which is pivoted to the supporting frame and the other arm has a curved slot 34 therein which engages a pin 35 which is adjustably mounted on a shaft 36 which is rotatably mounted in the supporting frame and which passes through a hole in the bottom of the casing where it is connected with the stem of a valve 37 which is located in the fuel line of the vehicle. A rod 38 connects the bolt with a slide 39 10 which is mounted in guideways 40 in the back of the casing. This slide carries the double contacts 41 and the single contacts 42 which are adapted to engage the contacts 43, 44 and 45 in the casing. The contact 41 is connected with the ignition line as is also the contact 44 so that when these two contacts are in engagement the ignition line is completed when the ignition switch is turned on. The contact 43 is connected with the 45 circuit of an alarm 46 so that when the contact 41 engages the contact 43 the alarm circuit will be closed when the ignition switch is moved to closed position. The contacts 42 and 45 are located in the magneto circuit.

55 From the above it will be seen that when the driver leaves his car and wishes to lock the same it is simply necessary for him to move the bolt toward the right by the handle so as to cause the bell crank lever 33 60 to close the fuel line by means of the valve 37 and to break the ignition circuit by means of the slide 39. This movement of the slide also closes the circuit to the alarm 46 so that when the ignition switch 65 is turned the alarm will be sounded. The

bolt will be held in its locking position and against the action of the spring by the locking means 26 and 28. As before stated the formation of the latch 26 on the bolt will permit the same to be moved to its locking position irrespective of the position of the combination disc but the bolt cannot be moved forwardly until the discs are in a position with their key-ways in alignment with the key-way in the sleeve. 75 When the driver wishes to use the car again he must first set the discs in their proper order to place their key-ways in alignment with the key-way in the sleeve and then he releases the latch 26 by turning the shaft 28 by means of the knob 29. The spring then moves the bolt forwardly so as to reset the ignition circuit and open the fuel line.

It is thought from the foregoing description that the advantages and novel features 85 of my invention will be readily apparent.

I desire it to be understood that I may make changes in the construction and in the combination and arrangement of the several parts, provided that such changes fall within 90 in the scope of the appended claims.

What I claim is:—

1. A lock of the class described including a housing, a supporting frame arranged within the housing, a sleeve carried by the supporting frame having a key way, a plurality of disks rotatably mounted upon the sleeve and each having a key way adapted to be aligned with the key way in the sleeve, a sliding bolt having one end recessed and movably mounted in the sleeve, means normally urging the bolt toward an unlocked position, a spring latch carried by the bolt, a head on one end of the latch formed with a beveled face, manual means for moving said bolt to a locking position and means on one of said disks cooperating with the head of the latch whereby upon movement of the bolt the latch will be forced into the bolt recess whereby said bolt may be moved to a locking position regardless of the position of the key ways, and another of said disks being formed in one face with an annular recess adapted to receive the head of the latch when the bolt is moved to a locked position to prevent movement of said bolt toward an unlocking position until the key ways in said sleeve and disks have been moved to aligning positions.

2. A lock of the class described including a housing, a supporting frame in the housing, a sleeve carried by the supporting frame having a longitudinal key way, a plurality of disks mounted for rotation upon the sleeve and having key ways adapted to be 125 aligned with the key way in the sleeve, a locking bolt slidably mounted within said sleeve and having a recess in one end, a spring latch carried by the locking bolt, having a head formed with a beveled face, 130

means normally urging the bolt to an unlatching position, means for manually moving said bolt to a locked position, means on one of said disks cooperating with the beveled face of the head whereby to permit movement of the bolt to a locked position regardless of the position of the key ways, means for retaining said bolt in a locked position, means for manually actuating said

retaining means to release said bolt, one of the remaining disks having an annular recess for receiving the head of the latch when the bolt is moved to a locked position to prevent movement of the bolt until the key ways in the disks have been moved to an aligning position.

In testimony whereof I affix my signature.

SAMUEL D. HOUSE.
